UNITED STATES PATENT OFFICE

161,755

CONDIMENT SHAKER

Guy T. Hopkins, Pendleton, S. C.

Application January 26, 1950, Serial No. 7,485

Term of patent 14 years

(Cl. D44—22)

To all whom it may concern:

Be it known that I, Guy T. Hopkins, a citizen of the United States, residing at Pendleton, in the county of Anderson and State of South Carolina, have invented a new, original, and ornamental Design for a Condiment Shaker, of which the following is a specification, reference being had to the accompanying drawing, forming part thereof.

Figure 1 is a top plan view of a condiment shaker, showing my new design.

Figure 2 is a front elevational view thereof.

Figure 3 is a vertical sectional view taken substantially on the plane of the line 3—3 of Figure 1, looking in the direction of the arrows, and

Figure 4 is a side elevational view of the same.

I claim:

The ornamental design for a condiment shaker, as shown.

GUY T. HOPKINS.
